UNITED STATES PATENT OFFICE.

SAMUEL J. WEAVER, OF ST. LOUIS, MISSOURI, ASSIGNOR OF ONE-HALF
TO JOHN O'BRIEN, OF SAME PLACE.

FEED-WATER HEATER.

SPECIFICATION forming part of Letters Patent No. 330,650, dated November 17, 1885.

Application filed December 9, 1884. Serial No. 149,828. (No model.)

To all whom it may concern:

Be it known that I, SAMUEL J. WEAVER, of the city of St. Louis, in the State of Missouri, have invented a certain new and useful Improvement Feed-Water Heaters, of which the following is a full, clear, and exact description, reference being had to the accompanying drawings, forming part of this specification, and in which—

10 Figure 1 is an elevation or side view of my improved feeder. Fig. 2 is a vertical section of same. Fig. 3 shows the device applied to an outside receiver, from which the boiler is fed. Fig. 4 is a vertical section of 15 a trap to prevent steam entering the supply-pipe.

My present invention relates to an improvement on Letters Patent No. 304,679, issued September 2, 1884, to myself and as- 20 signee, Jno. O'Brien; and this invention consists in features of novelty hereinafter fully described, and pointed out in the claims.

Referring to the drawings, A represents part of a boiler, and B the feed-pipe. 25 C represents a tank into which the water is discharged from the feed-pipe. It has a screw-threaded neck, D, by which it is secured to the pipe, or it may be secured by other suitable means. It has openings I for 30 the escape of the water, as indicated by arrows, Fig. 2, and above these openings is a hood, J, that deflects the water as it escapes through the openings I. The hood is held down by a collar, L, fitting on the feed-pipe between the hood and the boiler. The feed-pipe extends down into the tank, so that it is 35 submerged in the water therein, and thus steam is prevented from entering the supply-pipe and cracking it, while the feed of the 40 water is not interfered with. On the outside of the tank I prefer to cast flanges or ribs N, increasing in size downward, over which the water falls, dropping from one to another through the steam, which causes it to be 45 thoroughly heated before it falls to the water in the boiler. The tank, including its neck D and flanges N, is cast in one piece of metal, and the part of the supply-pipe that extends down into the tank is preferably dis-

connected from the main length, as shown at 50 O, Fig. 2, and formed in one piece with the collar L.

Fig. 3 represents how the feeder may be applied to a separate tank or receiver, from which the boiler is supplied with warm water 55 in the usual manner, through a pipe, P, the steam from the boiler entering the receiver through a pipe, T. The tank or receiver has a man-hole, W.

In Fig. 4 a modified form of trap is shown, 60 which consists in turning the end of the supply-pipe upward, forming a water-trap, V, that will effectually prevent steam entering the supply-pipe.

The tank is preferably larger at its lower 65 than at its upper end, so that it is in the form of a frustum, and the flanges N could be dispensed with, though I prefer not, as the water will run down the outside of the tapering tank, and will not be discharged directly 70 into space from the openings I.

My improved device acts to purify the wa- 75 ter, as well as to heat it.

I claim as my invention—

1. In a boiler feeder and purifier, the com- 75 bination of the feed-pipe and tank, the latter having flanges on its outside increasing in size downward, substantially as and for the purpose set forth.

2. In a boiler feeder and purifier, the com- 80 bination of the feed-pipe and tank, the former being submerged in the latter, and the latter having flanges increasing in size downward, substantially as and for the purpose specified.

3. In a boiler feeder and purifier, the com- 85 bination of the feed-pipe and a tank having openings for the escape of the water, and external flanges or ribs projecting into the steam-space, substantially as set forth.

4. In a boiler feeder and purifier, the com- 90 bination of the feed-pipe, tank, and hood, the tank having openings beneath the hood for the escape of water, and having flanges or ribs increasing in size downward, substan- 95 tially as and for the purpose set forth.

5. In a boiler feeder and purifier, the com- bination of the feed-pipe and tapering-tank

having discharge openings, substantially as set forth.

6. In a boiler feeder and purifier, the combination of the feed-pipe and tapering tank, the latter cast with a neck and openings beneath the neck, substantially as set forth.

7. In a boiler feeder and purifier, the combination of the feed-pipe, a tapering or frus-

to-conical tank, openings in said tank near its upper or smaller end, and a hood projecting over said openings, as set forth.

SAMUEL J. WEAVER.

In presence of—

GEO. H. KNIGHT,
SAML. KNIGHT.
